UNITED STATES PATENT OFFICE.

HIRAM G. SEDGWICK, OF MILL VALLEY, CALIFORNIA, ASSIGNOR TO THE NATIONAL SAFETY APPLIANCE COMPANY, A CORPORATION OF CALIFORNIA.

TRAIN SIGNALING AND STOPPING SYSTEM.

1,232,860.

Specification of Letters Patent.

Patented July 10, 1917.

Application filed November 22, 1912, Serial No. 732,982. Renewed May 10, 1917. Serial No. 167,802.

To all whom it may concern:

Be it known that I, HIRAM G. SEDGWICK, a citizen of the United States, and a resident of Mill Valley, county of Marin, State of California, have invented certain new and useful Improvements in Train Signaling and Stopping Systems, of which the following is a full and clear specification, reference being had to the accompanying drawings, in which—

Figure 1 is a diagram view of a portion of a road bed showing one manner of arranging the wiring and other apparatus of my system;

Fig. 2 is a similar view showing, as a continuation of Fig. 1, a portion of the adjacent block;

Fig. 3 a diagram of a preferred form of arranging the devices for a single road bed magnet.

My present system is especially adapted for that type of system in which the signaling or train stopping devices in the cab are put into action through the medium of magnetism generated by a magnet of suitable construction on the road bed; for instance, my present invention has relation to that type of system covered by my former patent numbered 896332, dated August 18, 1908, in which an electromagnet on the road bed is energized and the influence of this magnet so affects an armature on the passing vehicle as to operate a suitable signal or a train stopping device.

I have shown my present invention applied to the well known bonded-rail closed-circuit signal system, the track battery being shown at *a* and the main relay being shown at *b*, the blocks being as usual separated by insulated joints *c*. The main relay, as usual is located at one end of the block, and the track battery is as usual located at the other end of the block, and the short insulated rail sections which I locate at different points in the length of the block are spanned by conductors *d* in the usual manner, so as to keep the circuit between the relay and the battery continuously closed.

From the relay extends two line circuits, one (*e*) of which extends backwardly to the block next in the rear and the other one (*f*) of which extends forwardly into the block next ahead, crossing the track and terminating near the end of the block. When the main relay is deenergized the circuit *e* is

opened by the release of an armature *g*, and the circuit *f* is opened by the release of an armature *h*. In each of the circuits *e* and *f* is placed a battery, respectively lettered *i* and *j*. In each of the circuits *e* and *f* is arranged in multiple a series of auxiliary relays *k*, which are deenergized simultaneously with the main relay and serve to control the various electromagnets on the road bed. Assuming that a train has entered block A and is therefore moving toward the right, the main relay *b* at the far end of the block will break circuits *e* and *f* and thus deenergize the relays *k* in the block B just ahead and also in the block in rear of block A. The road bed magnets in the block in rear will be so located as to influence the armatures of any trains attempting to get into block A from the rear, and the magnets in block B will be so located as to affect the armatures of any trains that may attempt to get into block A through block B.

I prefer locating a series of five electromagnets near the end of each block, these magnets being lettered respectively *S'*, *S*, *R*, *G*, *Y*. The magnet *S'* is nearest the end of the block and is located adjacent to a pair of short insulated rail sections *l* and is connected to one of the relay devices *k* by conductors *m*. The next magnet *S* is arranged adjacent a pair of insulated short rails *n* and is connected to an adjacent relay device *k* by wires *o*. The next magnet *R* is similarly arranged in relation to insulated short rail sections *p* which abut the rail sections *n* and this magnet *R* is also connected with its auxiliary relay mechanism by wires *q*. The magnets *G* and *Y* are arranged side by side and adjacent to short insulated rail sections *r* and are each connected to the same auxiliary relay device respectively by wires *s* and *t*. The magnets which are intended to coöperate with trains going to the right are preferably arranged all at the right of the center of the track and are located out of alignment with each other, so that each magnet will be so located as to operate or influence but one of a series of armatures carried by the train. One set of armatures will be arranged at the right hand side of the train vehicle for coöperation with the series of magnets located to the right of the center of the road bed, while another set will be located on the other side of the center of the train vehicle for coöperation with

the other set of magnets when the train is going in the opposite direction. I have illustrated a preferred arrangement of armatures in a co-pending application serially numbered 733,162 but it will be understood that my present invention may be employed in connection with other armature arrangements.

The circuit arrangement which I prefer using in connection with magnets S' , S and R is illustrated in Fig. 3. The magnet circuit m includes a battery u , this circuit being constantly closed; a resistance v being included in the circuit to reduce the flow of current to a very small electromotive force, the idea being to keep the battery from deteriorating by non use. This circuit m at one side of the resistance is connected by a wire w to one of the short rails l and at the other side by a wire x to the other short rail l , this latter circuit including an armature y , which is controlled by the adjacent relay k , this armature being held in open position while the relay k is energized. When relay k is deenergized, armature y acts to close circuit x , so that should a train enter upon the short rails l at that time the wheels and axles of the train will, together with wires x and w , shunt the resistance v and throw the full strength of the battery into the magnet and thus completely energize the magnet and render it capable of causing the desired disturbance of its armature on the passing train. In the circuit w I arrange a suitable circuit breaker which will be actuated by the train, as soon as it passes off the short rail section l so as to thereby deenergize the road bed magnet. For this purpose I provide another insulated short rail section of track a' and connect these short rails by a conductor b' in which is arranged a resistance c' , the conductor b' at each side of the resistance being connected to a circuit d' in which is included a magnet f' and a local battery g' . The first pair of wheels of the train that passes onto the rails a' shunts the resistance c' and throws the full strength of the battery into the magnet f' and thus causes it to attract an armature h' , which armature is included in circuit w and is held in a normal closed position by a suitable spring or by gravity. The resistance c' is employed in order that the battery may be kept in constant use and thus prevent it from deteriorating but it will be understood that the resistance is sufficient to prevent enough current passing through it to energize the magnet f' . With this automatic circuit breaker it will be observed that the current from battery u is cut off from magnet S' the instant the first pair of wheels enters upon the short rail section a' , the main object being to thus prevent waste of current, it being no longer necessary to keep magnet S' energized after the passage thereover of its companion ar-

mature on the train. In Fig. 1 I have shown but one of these cut-outs (in connection with magnet S') but it will be understood that it is preferable to use one with each of the other electromagnets to the end that the instant the magnet has performed its function the energizing current shall be cut off from it. These cut out devices are especially valuable in thus saving current when, as sometimes happens a train will stop with some of its wheels on one of the short rail sections, in which event if the magnet is not cut off from its battery a great waste of current and possible exhaustion of the battery will result.

The magnets S and S' are, as stated, in alignment, and they are intended to actuate armatures which will cause the brakes of the train to be applied, two of these train stopping magnets being employed out of abundance of precaution. The next magnet R is preferably employed to actuate an armature which will cause a danger signal such as a red lamp and a whistle to be operated in the cab; and the pair of magnets G , Y , are preferably used in connection with a pair of armatures which will respectively actuate "safety" and "caution" signals in the cab, preferably green and yellow lamps and differentiated whistles. With this arrangement it will be observed that if the block ahead be unoccupied the engineer will get the green or safety signal but if occupied the engineer will first get the yellow or caution signal; then the danger signal; and if he proceeds farther he will be stopped either by S or S' . It will be understood that the short rail insulated sections will be of the proper length and properly positioned with respect to each other and the end of the block and also the respective magnets.

When the safety and caution magnets G and Y are employed in my system and they are associated side by side as shown, I prefer the wiring arrangement illustrated in my co-pending application serially numbered 798,251. With the system of wiring shown in this co-pending application, should the block ahead be empty and a train pass upon the short rails r , the first pair of wheels entering upon said rails will send the full power into the safety magnet G and thus give the safety signal in the cab; and should a train be in the block ahead which has therefore deenergized relay k , the wiring is such that the entry of the first pair of wheels upon the track rails r will throw its full strength into magnet Y and thus fully energize the same. It will be understood, of course, that any other system of wiring may be employed for these two magnets G and Y and also that the arrangement described for each of the magnets S , S' and R may be employed for each one of the magnets G and Y . The arrangement for these two magnets shown in my aforesaid co-pending applica-

tion is designed solely to enable me to use a common battery for these two magnets.

I desire it understood that this application is subordinate to my copending application 5 Serial No. 798,251, and that, therefore, nothing is claimed in this application that is covered by said copending application.

Having thus described my invention, what I claim as new and desire to secure by Letters Patent, is—

- 10 1. In a system of the class set forth, a short rail section insulated from the main rails, an adjacent magnet for actuating a signal or stopping device on a passing vehicle, a local battery and a resistance in normally closed circuit with said magnet, of means for cutting out said resistance and letting the full current through the battery consisting of two partial circuits connected respectively 15 to said short rails and to the magnet circuit at opposite sides of the resistance and a relay-operated switch in one of these partial circuits, the other one of these partial circuits being provided with a circuit breaker

which will be actuated by the first wheels of 25 the train which pass off the aforesaid short rail sections, and means whereby a train entering an adjacent circuit actuates said relay.

- 20 2. In a system of the class set forth, a magnet on the roadbed for actuating a train-controlled device on the train, a local battery for energizing this magnet and a resistance in circuit with the battery and the magnet to prevent the full current from going into the magnet, means for cutting out the resistance 30 35 operable by a passing train, said means embodying a pair of insulated rail sections, and automatic means for restoring the resistance operable by the train which cut out the resistance, said operation taking place when 40 the first wheels of said train pass off said insulated rail sections.

In testimony whereof I hereunto affix my signature in the presence of two witnesses.

HIRAM G. SEDGWICK.
